UNITED STATES PATENT OFFICE.

JAMES H. MURPHY, OF ST. LOUIS, MISSOURI.

EXCAVATING-BUCKET.

1,033,822.

Specification of Letters Patent. Patented July 30, 1912.

Application filed May 3, 1912. Serial No. 694,924.

To all whom it may concern.

Be it known that I, JAMES H. MURPHY, citizen of the United States, residing at St. Louis, State of Missouri, have invented

5 certain new and useful Improvements in Excavating-Buckets, of which the following is a full, clear, and exact description, reference being had to the accompanying drawings, forming a part hereof.

10 My invention has relation to improvements in excavating buckets; and it consists in the novel details of construction more fully set forth in the specification and pointed out in the claim.

15 In the drawings, Figure 1 is an elevation of an engine and boom, showing my improved bucket in service, the bucket being in position ready for dumping; Fig. 2 is a side view of the bucket after being dumped 20 and lowered to the ground; Fig. 3 is a similar view showing the tackle-blocks with their dogs lowered into engagement with the bucket lever-frames, and ready to be actuated for scooping; Fig. 4 is an enlarged 25 front view of the bucket in Fig. 1, looking at right angles thereto; Fig. 5 is a horizontal section on the line 5—5 of Fig. 1; and Fig. 6 is a diagrammatic view showing 30 the cable connections between the tackle-blocks carrying the dogs.

The object of my invention is to construct an excavating apparatus of the bucket or "clam-shell" type in which the usual three-drum engine shall be dispensed with, two 35 drums being all that is required to operate my improvement.

A further object is to construct a bucket the pulley-blocks of which shall always be clear of the dirt or earth which is being 40 excavated; one which is simple in construction, responsive to the manipulations of the operator, and one possessing further and other advantages better apparent from a detailed description of the invention which is 45 as follows:—

Referring to the drawings, B represents a conventional boiler, and E an engine deriving its steam from the valve-controlled steam pipe P, said engine operating the 50 hoisting-drum D. Mounted on a shaft in alignment with the shaft of the drum D is a drum D' operated from a similar engine (not shown) on the opposite side of the boiler, which derives its steam supply from pipe P', the drum D' controlling through 55 suitable tackle T, the position of the boom

Swinging about the post or mast M. These features are shown only conventionally as they are well understood in the art and no novelty is claimed therefor.

60

Leading from the drum D and passing over sheaves 1, 2, 3, is a suspension cable 4 adapted to wind about said drum, the outer end of the cable being connected to the cable bail 5 the ends of which are in turn 65 secured to the pulley or tackle blocks 6, 6, after being passed in proper direction around the pulleys of said blocks. The blocks 6 are secured between the free ends of the pairs of oscillating arms 7, 7, secured at the outer corners of the blocks, the opposite ends of the arms being hinged about the hinge-rod 8, the latter serving as a common axis for said oscillating arms 7, 7, and for the oscillating U-shaped hinged lever-frames 9, 9, of the scoops or buckets 10, 10. As shown in the drawings, the arms of one frame 9 are secured to the outer faces of the end walls of a scoop, the arms of the opposite frame being secured to the inner 80 faces of the end walls of the opposite scoop, so that when the scoops are closed the opposite edges of the end walls of the respective scoops will be brought into abutting, instead of a shearing relation. The closed 85 scoops form a bucket within which the scooped dirt is confined until released by the dumping mechanism presently to be described. Connecting the bottoms of the scoops with the lower outer corners of the 90 pulley-blocks are cables 11, 11', as shown. Disposed along the middle or transverse member of the U-shaped hinged frame 9 and having its ends bent around and secured to the sides of the frame, is a keeper or plate 95 12 with an outer bevel face as shown, said keeper being adapted to be engaged by the locking arm (short arm) of a latch or dog 13 pivoted at the inner upper corner of the pulley-block 6, the terminal looped ends of 100 the long arms of the dogs being secured to a common cable or rope 14 to which in turn a single dumping or tripping rope 15 is secured.

It may be stated in passing that each 105 block 6 has two pulleys, 6', 6', the cable 5 having a section passing over corresponding pulleys of the two blocks in one direction and having its end secured to one block, the opposite section passing in the opposite 110 direction over the remaining pulleys of the blocks and having its end secured to the

opposite block. This is shown to best advantage in the diagrammatic view in Fig. 6, from which it is obvious that a draft or pull on the bail portion of the cable 5 (that portion coupled to the cable 4) will cause the blocks 6, 6, to approach one another thereby oscillating the arms 7, 7, upwardly, (Fig. 2) and a release of the bail 5 will permit the blocks 6, 6, to drop down and hence 10 oscillate the arms 7 downwardly in which latter movement the dogs assert themselves in a manner to be fully understood from a description of the operation of the bucket, which is substantially as follows:—The 15 buckets or scoops 10 and their respective controlling lever-frames 9 are so balanced that when released the buckets open out substantially as shown in Fig. 2, the frames assuming a horizontal position, beyond 20 which they can not drop because limited by the back wall of the bucket. If (referring to said Fig. 2) we now slacken the rope 4 and bail 5, by unwinding the rope off the drum D, the blocks 6 will drop down until 25 they rest on the frames 9 (Fig. 3) in which movement the dogs 13 (pivoted to the blocks) are caused to automatically engage the keepers 12 (the rope 15 being left hanging loose so as not to exert any pull on the 30 cable 14) and thus lock the lever-frames 9 to the blocks. By now reversing the drum D so as to wind up and pull on the cable 4 (and bail-cable 5), the blocks will be caused to approach each other and will thus carry 35 the levers 9 with them. In this movement the levers oscillate about the hinge-rod 8 toward each other and hence cause the scoops 10 to close, in which closing movement the cutting edges of the scoops will 40 dig into the earth and scoop up a bucket full as well understood in the art. When the scoops are fully closed, the lever frames are about ninety degrees apart (Fig. 1) though this angle may vary. Assuming 45 that the bucket is full of dirt (Fig. 1) the operator gives the cable 15 a pull or jerk, this having the effect of tripping the dogs 13 so as to release them from their keepers 12 and hence from the frames 9. The release of the frames 9 allows the scoops to 50 part, the bucket thus opening and dumping the dirt at any point depending on the position of the boom L. The release of the blocks 6, 6, from their respective lever-frames 9 causes them to approach one an-

other still more (Fig. 2) though they never carry the arms 7 to a "dead center", so that the latter are free to drop the moment the buckets are lowered to the ground for another cut (Fig. 3) in which drop they 60 again bring the dogs into locking engagement with the keepers 12. This being done, a draft on the cable 4 will again close the scoops and the operation is repeated. Obviously, the dumping of the buckets or 65 scoops 10 is facilitated by the draft exerted on the connecting cables 11, 11', the sudden release of the blocks 6, from the levers 9 upon the tripping of the dogs causing a pull on said cables and assisting in opening the 70 buckets.

As seen from Fig. 3, which represents the bucket on the point of scooping the dirt, the tackle blocks and cables are raised above the surface operated on, so that these parts 75 are always clear of the dirt and remain clean. The buckets when released and as they are being lowered to the ground G open out so as to bring the lever frames 9 into a substantially horizontal plane in 80 which position the keepers 12 on the frames become engaged by the dogs 13, the latter by reason of the weights of their long arms readily gravitating into locking engagement with said keepers provided the rope 15 is 85 left perfectly free.

Having described my invention, what I claim is:—

In combination with a pair of buckets and lever arms hinged about a common axis, independently oscillating arms hinged about the said axis and free to move to and from the lever-arms of the buckets, tackle-blocks in co-operative connection with one another secured to said oscillating arms, means for 90 locking the latter to the lever arms of the buckets with a movement of the tackle-blocks toward said bucket-lever-arms, means for releasing said locking means, and a cable connection between the buckets and 95 oscillating arms whereby upon release of the locking means the oscillating arms may exert a draft on the buckets and assist in opening the same.

In testimony whereof I affix my signature, in presence of two witnesses.

JAMES H. MURPHY.
